LIQUID DISPENSER

Emil Schwarzkopf, Chicago, Ill.

Application March 18, 1943, Serial No. 479,557

10 Claims.

(Cl. 225—22)

The object of the present invention is to produce a simple and novel attachment for a bottle or other container to permit liquid to flow freely therefrom, upon demand, and to be replaced by air; the discharge outlet and the air inlet being effectively sealed except at times when liquid is being withdrawn.

In all of the devices of this same general character with which I am familiar, there is a substantial amount of dripping of liquid after the normal flow has been shut off. One of the purposes of the present invention is to overcome this defect.

All of the devices with which I am familiar have heretofore been composed mainly of metal which rusts, corrodes, or otherwise responds to chemical reaction with many liquids, with the result that the liquids are contaminated thereby. In the case of wine, for example, a metallic taste may be acquired when in contact with metal for considerable time. A further object of the present invention is to produce a dispensing device which will not be chemically acted upon by the liquids which are usually dispensed through devices of the general type under consideration.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a central longitudinal section through a dispensing device constructed in accordance with the present invention, the intermediate part between the two ends being broken away; Fig. 2 is a top plan view of the device, showing only the upper end; and Figs. 3, 4, 5, 6 and 7 are sections taken, respectively, on lines 3—3, 4—4, 5—5, 6—6 and 7—7 of Fig. 1.

Referring to the drawing, 1 represents a closure for the opening in a container through which liquids are to be discharged; the same being shown as taking the form of a cap adapted to be screwed upon the neck of a bottle A. The cap has a long hub-like projection 2 on the under or outer side thereof and coaxial therewith. The lower half 3 of this projection is smaller in diameter than the upper half and it terminates in an extension 4 of still smaller diameter, which may be termed a spout or, since the bore 5 in the part 4 continues up through the part 2 and through the flat wall of the cap, the entire project-

tion may be regarded as a spout. At the extreme lower end of the spout is a narrow, inturned flange 6 that provides a seat for a valve 7 arranged within the spout.

It will be seen that when the bottle or other container is tilted far enough or turned upside down, liquid can flow through the bore 5 and out of the spout, provided the valve 7 be open. It will also be seen that since the valve seat is at the very outer end of the spout, the closure of the valve shuts off the flow of liquid completely and allows no dripping.

The cap is preferably composed of glass, although some plastic materials may be sufficiently inert to the liquids to be dispensed to make them satisfactory for my purpose.

Air is adapted to enter the container through one or more pipes or tubes 12 of small diameter, two being shown in the present instance. These, like the cap, are preferably made of glass. These two pipes are preferably screwed into the flat wall of the cap's inner side and are preferably long enough to reach almost to the bottom of the bottle, for example. The hub contains bores or passages 8 extending down through the same from the lower ends of the glass tubes or pipes. The ends of the glass tubes, remote from the cap, are fixed into a block 9 of plastic material or glass containing a chamber 10. Actually, the air flows through little tubes 11, preferably of metal, which extend through and fit slidably in the tubes 12. The bores or passages 8 are enlarged in diameter downwardly from a point that lies a short distance below the cap proper, as indicated at 12, and in these enlarged sections, surrounding the little metal air pipes 11, are compression springs 14. The lower ends of the pipes 11 extend down through and are fixed to the bottom wall of a cup member 15, that is, a sliding fit on the part 3 of the hub. The member 15 has a pair of radial arms 16 projecting in opposite directions therefrom. By pushing up on these arms, the member 15 rises, compressing the springs 14 and raising the pipes 11.

The upper ends of the pipes 11 are secured together by a cross-piece 18 lying within the chamber 10. In the upper side of the block 9 is a deep slot 19 extending diametrically across the block, and a port 20 extends through the web between the bottom of the slot and the top of the chamber 10. Cooperating with this port is a valve 21 which opens when it is lifted and closes when lowered. This valve has a stem 22 that extends down into the chamber 10 and is there attached to the cross-piece 18. The parts are so propor-

tioned that normally the springs 14, acting through the air pipes 11, draw the valve 21 down against its seat, thereby sealing the chamber 10 against escape of air into or the entry of liquid from the bottle or other container. However, when the cap 15 is pushed up as, for example, by pressing a tumbler B or other receptacle against the under side of the arms 16, the valve 21 is raised from its seat and air can escape from the chamber into the container whenever it must do so in order to replace liquid that is being discharged.

Means are provided to operate the liquid control valve 7 simultaneously with the air valve 21. In the arrangement shown, the block 9 has in the sides thereof diametrically opposed longitudinal slots or grooves 24 whose upper ends merge into the ends of the slot 19. Straddling the unmitigated portion of the block bounded by the bottoms of the three slots, is an inverted U-shaped yoke 25 to which the air valve is attached and which is slideable up and down on the block. This attachment may be effected by simply extending the valve stem through the valve proper as indicated at 26 and through the cross-piece of the yoke, and applying a nut 27 to the free end of the part 26. Between the free ends of the arm of the yoke there is disposed the upper end of a short link or bar 28, secured to these arms by a hinge pin 29 that permits relative swinging movements. Thus, while the yoke is prevented from moving in any direction except up and down, the part 26 has an additional capacity for swinging movements. Screwed into the lower end of the part 28, for purposes of lengthwise adjustment, is the stem of a socket member 30. This socket member has an internal annular groove 31 into which lead two short longitudinal grooves 32 starting at the mouth of the socket. Extending into the socket is the upper end of a rod 34 provided with a pin 35 extending transversely through the same and projecting a short distance therefrom at each end. In order to assemble the rod in the socket, it is aligned with the latter and turned about its axis until the ends of the pin 35 register with the two grooves 32. The rod is then pushed into the socket until the pins register with the annular groove 31; whereupon, by giving the rod a half turn, it is locked to the socket.

The lower end of the rod 34 is connected to the valve 7. This connection is preferably a yieldable one so as to permit the valve 7 to be closed ahead of the air valve, while permitting the air valve to continue its movement until it is firmly seated. In the arrangement shown, the valve 7 has a short stem 36 which extends loosely through the bottom of an elongated cup-shaped element 37, screwed upon the lower end of the rod 34. The stem is provided with a head 38 within the cup, thereby preventing it from being pulled out. Within the cup is a compression spring 39, resting on the head 38 and bearing against the lower end of the rod 34.

It will be seen that normally both valves are held closed by the springs 14 which are more powerful than spring 39, so that the latter spring will be compressed to a degree necessary to allow the air valve 21 to seat, after the valve 7 is seated. By this means the complete closing of both valves is assured. Therefore, when the device is attached to a bottle, for example, no liquid can escape from or air enter the bottle even when the bottle is turned upside down, as shown. In order to draw liquid from the bottle, a receptacle, such as indicated at B, is simply positioned under the inverted bottle and pushed up against the arms

16. This causes the air pipes to move up, raising the air valve and, through the latter, the valve 7. As liquid flows out of the spout, air to replace the liquid, flows from the air chamber in the block 9 past the air valve into the bottle to displace the liquid flowing out of the bottle. It will be seen that the air pipes 11 support the cap 15, with its receptacle-engaging arms by means of which the pipes are raised; open the air valve 21 when the pipes are moved up; permit air from the surrounding atmosphere to flow up through the same, when up, into the air chamber in block 9; and, because the main valve 7 is suspended from the air valve, cause the main valve to open and close in proper time relation to the opening and closing of the air valve. When the receptacle B is lowered, the valve 7 closes promptly and since its seat is at the very end of the spout the flow of liquid instantly ceases, no liquid remaining in the spout below the valve to produce dripping. Also, because the air valve does not close before the main valve, no objectionable vacuum is created within the bottle to delay the start of liquid flow when the next dispensing operation occurs.

25. It will also be seen that the liquid does not come in contact with any metallic part the corrosion of which would result in contamination of the liquid as well as affecting the efficiency of the dispensing device; the yoke 25, link 28, socket member 30 and rod 34 being composed of glass or plastic material as are the cap 15, block 9 and tubes 13. Since its exposed surfaces are of glass or the like, the device is easily cleaned.

Should it be desired to remove the main valve 35 for any reason, this can be done quickly, easily and safely. The rod 34 need be given only a half turn and then be withdrawn from the socket 28 while the valves are up in order to detach the rod and permit it and the main valve to be lifted out of the device.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

50. 1. A device for attachment to a container for liquids to dispense the liquid, comprising a member having a spout for the discharge of liquid, a valve in the outlet end of the spout, a pair of tubes extending from said member in the opposite direction from said spout, a block secured to the upper ends of the tubes and having a chamber in communication with the tubes, an air valve associated with said chamber, a rod connecting said valves together, and spring-held air pipes the lower ends of which open into the atmosphere surrounding the spout slidably mounted in said member and extending from beside the spout into the block and to the air valve to open and close the same.

65. 2. A device for attachment to a container for liquid to dispense the liquid, comprising a member having a spout for the discharge of liquid, a valve within and at the outlet end of the spout, an air pipe extending from said member in the opposite direction from said spout, an air valve at the end of the air pipe remote from said member, a rod connected to the air valve and extending into the vicinity of the other valve, and a yieldable connection, including a compression spring, between the rod and the latter valve

to permit it to seat a little ahead of the air valve.

3. A device for attachment to a container for liquid to dispense the liquid, comprising a member having a spout for the discharge of liquid, a valve within and at the outlet end of the spout, an air pipe extending from said member in the opposite direction from said spout, an air valve at the end of the air pipe remote from said member, a yoke connected to the air valve, a rod attached to said yoke by a quickly-detachable connection and extending into the vicinity of the other valve, and a yieldable connection including a spring between the rod and the latter valve to permit it to seat a little ahead of the air valve.

4. A device for attachment to a container for liquid to dispense the liquid, comprising a closure member having a spout for the discharge of liquid, a valve in the outlet end of the spout, an air pipe extending from said member in the opposite direction from said spout, an air valve at the end of the air pipe remote from said member, a slidible element connected to the air valve and movable with the same during the opening and closing of that valve, a socket element hinged to slidible element, and a rod connected at one end to the valve in the spout and having a quickly-detachable connection at its other end with said socket element.

5. A device for attachment to a container for liquid to dispense the liquid, comprising a closure member having a spout for the discharge of liquid, an outwardly seating valve in the outlet end of the spout, an air chamber remote from said member on the opposite side from that on which the spout is located, means placing said air chamber in communication with the atmosphere in the vicinity of the spout, an air valve at said chamber, a rod connected to the valve in the spout and extending toward the air valve, and means, including a quickly-detachable connection, securing the rod to the air valve.

6. A device for attachment to a container for liquid to dispense the liquid, comprising a member of glass forming a closure for the container and a spout for the discharge of liquid, a valve in the outlet end of the spout, a glass tube extending from said member in the opposite direction from said spout, an element containing a chamber fixed to the free end of the tube, an air valve associated with said chamber, means placing said chamber in communication with the atmosphere surrounding the spout, and means including an actuator simultaneously to operate the valves.

7. A device for attachment to a container for liquids to dispense the liquid, comprising a non-metallic closure member including a spout for the discharge of liquid, a valve in the outlet end of the spout, a non-metallic tube fixed to and extending from said member in the opposite direction from said spout, a non-metallic hollow block at the end of the tube remote from said

member, an air valve on the block to vent the interior of the latter to the space surrounding the block, a rod connecting said valves together, a spring-held air pipe slidably mounted in said member and extending from beside the spout through said member and said tube, said air pipe placing the interior of the block in communication with the atmosphere surrounding the spout, and means connecting said air pipe to the air valve to open and close the latter.

8. A device for attachment to a container for liquids to dispense the liquid, comprising a non-metallic closure member including a spout for the discharge of liquid, a valve in the outlet end of the spout, a non-metallic tube fixed to and extending from said member in the opposite direction from said spout, a non-metallic hollow block at the end of the tube remote from said member, an air valve on the block to vent the interior of the latter to the space surrounding the spout, a rod connecting said valves together, a spring-held air pipe slidably mounted in said member extending from beside the spout through said member and said tube, the outer end of the air pipe opening into the atmosphere surrounding the spout, means connecting said air pipe to the air valve to open and close the latter, a part on the outer end of said air pipe for engagement with a receptacle to receive liquid from the spout and move the air pipe inwardly to open said valves.

9. A device for attachment to a bottle or other container having a discharge opening, comprising a glass structure including a cap to form a closure for the discharge opening in the container, and having a short spout through which liquid is to be discharged, and an air chamber remote from the cap and adapted to be housed in the container, means having an air inlet in the cap to admit outside air into said chamber, the spout containing an internal valve seat in the vicinity of the outer end; a valve within the spout normally resting on said seat, and a connecting device composed of glass between said valves to cause them to move in unison with each other.

10. A device for attachment to a bottle or other container, comprising a cap member having a central depending spout provided with an internal valve seat at the outlet end, a pair of long tubes fixed to the inner side of the cap and projecting upwardly therefrom, a hollow block fixed to the upper ends of the tubes, a valve within the spout cooperating with said seat, an air valve on the block to vent air from the interior thereof into the container, a pair of air pipes extending through the length of the spout and through said tubes into the interior of the block, the air pipes opening into the surrounding atmosphere in the vicinity of the spout, springs acting on the pipes to draw them down, a connection between said pipes and said air valve, and a connection between said valves to cause them to move in unison with each other.
